(57) **CLAIM**

The ornamental design for a connector for lamp, as shown and described.

DESCRIPTION

FIG. 1 is a perspective view of a connector for lamp, showing my new design.

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is another perspective view thereof;

FIG. 9 shows the article in a position of use; and,

FIG. 10 shows the article in another position of use.

The even-broken line in the figure drawing views represents environment or portions of the connector for lamp that forms no part of the claimed design.
